Primary Examiner—Martie K. Holtje
Attorney, Agent, or Firm—Trapani & Molldrem**[57]****CLAIM**

The ornamental design for an appointment book leaf, as shown and described.

DESCRIPTION

FIG. 1 is a front elevation view of an appointment book leaf showing our new design; and,

FIG. 2 is a rear elevation view thereof.

The appointment book leaf is flat and of conventional thickness.

The stippled shading in the drawing indicates color contrasts.

The indicia "2000" depicted by means of broken lines in the upper lefthand corner of FIG. 1 has been shown for illustrative purposes only and forms no part of the claimed design.
